UNITED STATES PATENT OFFICE.

HARRY W. BOLENS, OF PORT WASHINGTON, WISCONSIN.

CHAIR-IRON.

1,272,365.

Specification of Letters Patent. Patented July 16, 1918.

Application filed March 18, 1918. Serial No. 223,193.

To all whom it may concern:

Be it known that I, HARRY W. BOLENS, a citizen of the United States, residing at Port Washington, in the county of Ozaukee and 5 the State of Wisconsin, have invented a new and useful Improvement in Chair-Irons, of which the following is a specification.

This invention relates to improvements in that construction of chair-irons employed in 10 revolving chairs and particularly typified in the construction of chair-iron illustrated and described in the pending application of one Charles J. Travers, filed August 4, 1917, Serial No. 184,395, or in any other construction 15 of chair-iron involving a hollow hub about which are fitted radiating supporting-legs clamped between upper and lower plates and in which the latter plate is independent of and slipped over the lower end 20 of the hub.

In the construction of chair-iron referred to above, the hollow hub is provided with intermediary radiating lugs which engage in corresponding openings formed in the ends 25 of the radiating legs. The upper end of the hub is provided with an integral flange and below the same and the upper surfaces of the legs is located the upper clamping-plate, screws passing through the plate engage the 30 legs. Slipped over the lower end of the hub and screwed to the undersides of the legs is the lower clamping-plate, and between the legs and engaged by the upper clamping-plate, are filling-blocks which rest at their 35 lower ends upon the lower clamping-plate and have their inner vertical edges mortised to correspond with those of the legs, whereby through the medium of the upper screws the upper clamping-plate may be drawn 40 down upon the upper extended ends of the filling-blocks and thus the latter forced inwardly so as to tightly wedge between the legs. In this construction it will be noted that much of the rigidity of the base thus 45 formed depends upon the connection between the hub and the legs, that is, the radiating studs and the openings in the legs for their reception, so that in the event of the wood drying out by long use and therefore shrinking, the legs are liable to become 50 loose and thus to a certain extent the base will lose its original rigidity.

My present invention has for its object to prevent this possibility and also to reduce 55 the cost of manufacture in a chair-iron of the type illustrated and referred to.

With these objects in view, the invention consists in a means for securing the bottom clamping-plate to the lower end of the hollow hub, (whereby I am enabled to omit the radiating studs and corresponding holes hereinbefore referred to,) thus clamping the legs in position and also saving the cost of material and workmanship in forming the lugs and holes. 65

Referring to the drawings:

Figure 1 is a vertical longitudinal sectional view, the lower portion of the hub being illustrated in side elevation, of a chair-iron of the type mentioned and embodying 70 my improvements;

Fig. 2 is a horizontal sectional view of the same on the line 2—2 of Fig. 1 looking in the direction of the arrows;

Fig. 3 is a detail view showing the lower 75 bottom clamping-plate in top plan view and the hollow hub in cross-section, these parts being shown in the relative positions they occupy after the bottom clamping-plate has been slipped upon the lower end of the hub 80 and before the plate has been rotated to a binding locked position upon the hub; and

Fig. 4 is a bottom plan view in detail of the bored hub.

Similar numerals of reference indicate 85 similar parts in all the figures of the drawings.

Referring to the drawings for the purpose of describing particularly the typification of chair-iron to which my improvements are applicable, 1 designates the hub, usually cylindrical; but which may be of any other external shape. This hub is preferably of cast iron, provided with a central longitudinal bore 2, extending throughout 90 the same, and terminates at its upper end in an integral annular flange 3, at one side of which is formed a short vertical standard 4, transversely perforated and threaded, as at 5, for a stop-screw 6, the inner end of which 95 extends inwardly to a point beyond the standard.

Mounted to revolve within the bore 2 of the hub, is the usual adjusting-standard 10, provided with the longitudinal groove 11 105 and with threads which in the present instance terminate above the lower end of the standard.

Fitting the hub 2 and positioned immediately below the annular flange of the same 110 is the upper leg clamping-plate 13, preferably of concavo-convex form in cross-sec-

tion and provided with screw-holes 14, coincident with the legs of the chair-base.

Fitting the lower end of the hollow hub is the lower leg clamping-plate 15, and the 5 same consists of an annular ring shaped plate 16, and radial arms 17, corresponding with the position and curvature of the undersides of the legs.

The legs 18, may be of any design desired, 10 and their inner ends may be slightly curved to conform to the exterior of the hub. The vertical inner corners of the legs may be cut away or chamfered, as at 20, and between each pair of legs is positioned a filler-block 15 21, of substantially triangular shape, the inner edge of such block being formed with an extension 22, in this instance of angular shape so as to adapt it to fit snugly between and conform to the portions 20 of the adjacent legs. When in position, it will be seen that the legs and blocks combine to form 20 the circle about the hollow hub.

In the present instance there are punched inwardly disposed tongues 23, from each of 25 the arms 17 of the lower leg clamping-plate, each tongue being perforated or provided with a screw-hole 24. Between the arms 17 the annular portion of the lower leg clamping-plate is provided with nail-holes 25.

30 The undersides of the legs 18 are provided with shallow cavities 26 terminating at their inner ends in abrupt shoulders 26^a, the cavities receiving the tongues and the ends of the latter abutting against the shoulders of said cavities.

When thus positioned it will be seen that the legs are clamped between the upper and lower clamping-plates 13 and 15, after which screws 27, are inserted downwardly 40 through the screw holes 14 of the upper plate 13, and screws 28, are inserted upwardly through the holes 24 of the tongues 23 and into the undersides of the legs.

The filler-blocks are inclined and inserted 45 upper end first under the concavo-convexed plate 13, and subsequently forced upward and inward, thus bringing them into vertical position and causing them to snugly fit between the legs. Nails 39, (see dotted lines 50 Fig. 2) are then driven upwardly through the perforations or nail-holes in the bottom leg clamping-plate and into said blocks, whereby the latter when once positioned and secured are prevented from lateral displacement.

55 The adjusting-standard 10 carries the usual J-washer 29, which by means of a spline 30, engages the groove 11 of the adjusting-standard, whereby the washer is prevented from rotation independent of the standard and yet is slidably mounted thereon. The washer is of the well known construction, its upper side being provided with shallow radial ribs designed to lightly engage with corresponding grooves formed in

the underside of the hub 31 of the usual hand-wheel 32, the hub being countersunk on its underside to receive the washer. To prevent the separation of the hub, hand-wheel, and washer, the hub is provided with 70 an external annular flange 33, over which normally engages the before-mentioned screw 6.

The hand-wheel is threaded on the screw or adjusting-standard, and by rotation of 75 the same, it will be seen that the wheel being held down by the screw 6, the screw or standard may be fed up or down and thus the chair, which it will be understood, is supported by the usual means upon the upper end of the standard, will be raised or lowered. On the other hand, it will be apparent that as the occupant revolves the chair, and consequently, the screw or adjusting-standard, the hand-wheel and J-washer will revolve together, the latter bearing upon and moving over the upper side of the annular flange 3 of the hub.

Thus far I have described the typical construction of chair-iron to which my improvements refer, such being the construction illustrated and described in the pending application hereinbefore referred to. I will now describe in detail my improvements.

I preferably though not necessarily omit the radiating lugs of the hub or their equivalents and consequently the holes in the ends of the legs designed for their reception, thus, in the event of such omission, 100 saving considerable expense in the manufacture of the chair-base.

Near its lower end I provide the hub with an external groove 35, the same being annular, shallow and eccentrically positioned 105 with relation to the hub in which it is formed, and I preferably provide a shallow vertical groove 36 (see Fig. 4,) extending from the lower end of the hub to the groove 35.

The cylindrical opening 37, formed in the annular plate or ring-portion of the lower leg clamping-plate 15, corresponds in diameter with the hub, in the present instance, and therefore is slightly larger than the 115 eccentric groove 35. At one point of its inner edge this ring is provided with a narrow lug or inward extension 38, the latter and the vertical groove 36 being of such relative size as to permit of the travel of 120 the lug or extension along said groove until the lug or extension reaches the eccentric annular groove 35 with which said vertical groove communicates.

As will be inferred from the foregoing, 125 the lower leg clamping-plate is slipped over the end of the hub, the lug or extension 38 passing up the groove 36 of the hub and entering the eccentric annular groove 35 at the deepest point of the latter. After 130

this, in order to lock the lower leg clamping-plate in position upon the hub, it is simply necessary to rotate said plate in either direction, or until the lug or extension 38 of the plate binds firmly against the wall of said annular groove. When in this position substantially the entire inner edge 5 of the opening in the lower leg clamping-plate will be supported by the eccentric groove and a few taps of the hammer 10 against the arms 17 of the plate, or one of them, will serve to force or impinge the lug 38 of the plate against the hub, so that the plate becomes bound and locked in position 15 immovably upon the hub, after which the remaining parts of the base may be positioned with relation to the lower plate and all secured together in a manner hereinbefore referred to or some equivalent manner, 20 as may be preferred.

Having described my invention, what I claim is:

1. In a chair-iron, the combination with a bored hub, an upper leg clamping-means, 25 and radiating legs, of a lower leg clamping-plate, said latter plate being adapted to slip over the lower end of the hub, and means for securing said lower leg clamping-plate in position upon the hub by a partial rotation of the plate thereon.

2. In a chair-iron, the combination with a bored hub, an upper leg clamping-means, and radiating legs, of an annular groove formed in said hub near its lower end, a 30

groove leading thereto and from the end of 35 the hub, a lower leg clamping-plate adapted to slip over the lower end of the hub and provided with an internal extension adapted to engage the grooves of the hub, and means for securing the leg clamping-plate within 40 the annular groove of the hub subsequent to a partial rotation of said plate.

3. In a chair-iron, the combination with a bored hub, an upper leg clamping-means, and radiating legs, of an annular groove 45 formed in the hub and eccentrically with relation to the same, a groove leading to the annular groove and from the lower end of the hub and communicating with the groove at its deepest point, and a lower leg 50 clamping-plate having an annular opening provided with an inward extension or lug, said plate being adapted to be slipped over the end of the hub and into the annular groove thereof and the extension or lug 55 being adapted to travel in the communicating groove and into the annular groove, whereby when said plate and lug are in engagement with the annular groove of the hub and said plate partially rotated the lug 60 or extension is caused to bind against the hub within the groove and thus secure the plate in position.

HARRY W. BOLENS.
